LUCIEN BÉGIN, OF PARIS, FRANCE, ASSIGNOR OF ONE-HALF TO WILLIAM B. WEAVER,
OF BIRMINGHAM, ALABAMA, AND HAROLD F. WILHELM, OF NEW YORK, N. Y.

RADIO FREQUENCY COMMUNICATION SYSTEM.

Application filed March 2, 1926, Serial No. 91,669, and in France March 13, 1925.

The present invention relates to a new method of remote control in signalling systems comprising the use of carrier waves transmitted with or without wires and, in particular, in signalling networks comprising a plurality of correspondents making use of but a limited number of signalling frequencies.

It is known that there exist duplex signalling networks comprising a plurality of correspondents which, just as in shipboard and coastal stations, make use of but one and the same stand-by wave-length and in which the calls are discriminated by the manual or automatic transmission of a given number of wave trains for each station, these impulses being selectively translated at the called station either into a single signal by means of mechanical selector mechanism or by the mere acoustic identification of a predetermined series of impulses.

On the other hand, it is also known that it is possible to establish a two-way communication between two stations such as M, N, providing reception at each station be made to take place at a wave frequency sufficiently different from that used therein for transmission, which amounts to say that station M must transmit waves of say frequency f^1 and receive on frequency f^2 whilst station N must do the opposite. When it is desired to extend this classical method of duplex signalling to a network comprising a plurality of correspondents such as M, N, O, P, it is obvious that the operation, at any given moment, must be restricted to the communication between any two stations with the momentary exclusion of all the other stations, just as in party lines comprising several subscribers' sets. In the latter case, however, it is usually possible for any subscriber whatever, other than the two already communicating, to listen in to what is going on over the line without the knowledge of the two active correspondents. In carrier wave duplex signalling, however, the apparatus is usually so designed that it suffices to lift the receiver off the hook so that the transmitting gear be automatically thrown into operative condition and the carrier wave itself emitted even if the operator does not modulate its amplitude by speaking in front of the microphone. It is obvious that, under such conditions, it is hardly possible for a third party to listen in to the communication taking place between

two other correspondents without the latter perceiving his interfering carrier-wave.

In accordance with one application of the present invention, the possibility of such disturbing carrier wave transmission by third parties is eliminated while yet allowing the third party to listen in. This is accomplished by first selectively calling the desired party only and then by locking the transmitting equipment of all the other stations comprised in the network. With this object in view, a given party shall be called by transmitting waves of the same frequency as that to which the stand-by apparatus of all the stations is tuned, and then by modulating those waves at a relatively low frequency, distinct for each station, as well as by designing the stand-by equipment of each station such as it will be operated distinctly by the carrier-wave itself and by the modulation thereof.

In the accompanying drawings:

Fig. 1 shows, by way of example, a form of the invention as applied to a network of correspondents making use of but two carrier wave frequencies for duplex communication between any two stations.

Fig. 2 illustrates another mode of carrying out the invention by the use of electron discharge tubes.

Referring now to Fig. 1, in this figure the terminals of the apparatus, leading to either the serial system in the case of wireless communication or to the line conductors in the case of wired communication, are denoted by 60. Those terminals lead, on the other hand, to two coupling systems 48^a—50^a—51^a—53 and 48—50—51—52 one of which is provided to transmit efficiently a given frequency, such as f^1 , to the exclusion of all other frequencies and particularly of frequency f^2 , whilst the other system is provided to do the opposite. Assume the arrangement designated by 48^a—50^a—51^a—53 is provided to efficiently transmit f^1 and the arrangement designated by 48—50—51—52 is provided to transmit f^2 . In that case, transformer 48^a should not permit the transmission of f^2 and, reciprocally, it should not be possible to transmit frequency f^1 through transformer 48. With that object in view, one of the windings of 48^a shall be shunted by a parallel circuit 50^a tuned to f^1 and having a high C/L ratio so as to offer but negligible reactance for short-circuiting all frequencies other than f^1 and then there shall be inserted

in series with one of the windings of 48^a, a resonant circuit 51^a, which shall offer a high impedance to waves of frequency f^2 which it is desired to particularly exclude 5 whilst behaving as a negligible impedance for waves of frequency f^1 . The opposite shall be done as regards the arrangement 48—50—51—52 having to transmit but waves of frequency f^2 , i. e., all frequencies 10 excepting f^2 will be highly shunted by the trap circuit 51 and then frequency f^1 in particular will be highly impeded by the series rejector 50 tuned to that frequency. By means of the relays 54, 55, each acting as a 15 double pole double-throw switch, it will be possible to assign either of these coupling units to the detector 56 and the other to the transmitter 31, or conversely.

During the stand-by period, the output of 20 detector 56 is connected to the exciting winding of a relay 40 through the primary of transformer 14^a having a trap circuit 13 across its terminals and serially through the back contacts of three other relays 41, 47 25 and 43. Relay 40 is shunted by a condenser 39 which by-passes the variable component of the current flowing therethrough. The secondary winding of transformer 14^a is branched to the terminals of a tuning condenser 15 in parallel with the exciting winding 58 of a tuning fork relay 57, each station 30 having a tuning fork relay having a distinct time period of its own. When the tuning fork 57 enters into vibration it closes the circuit of battery 22 through contacts 59 and the winding of a drop relay 20, the latter being shunted by a condenser 19 which bypasses the undulatory component of the current. The parallel circuit 13 is tuned to the 35 natural time period of the fork relay 57 at each station, and its object is to provide a shunt of negligible reactance to all modulation frequencies other than that intended to operate the fork relay 57 of the called station.

40 Terminals 33 of the transmitter 31 are intended to be connected to the modulating system, that is, to the keying arrangement in the case of telegraphic signalling and to the microphone system in the case of telephonic signalling, and, during the calling period 45 only, to a source of definite low frequency, distinct for each station to be called.

In the drawing the telephone transmitter 24 may be connected thru transformer 25 50 and filter 26 to the back contacts of relay 30. The front contacts of relay 30 may be connected selectively to either source of low frequency 28 or 29 depending on the position of key 27. Relay 30 may be operated by 55 depressing key 37. The low or modulating frequency source 28 or 29 may be connected according to which station it is desired to call. The armatures of relay 30 may be connected to terminals 33 of the transmitter 31 60 to modulate the high frequency output of

transmitter 31 with the desired modulating current.

While transformer 14^a at each station will be designed so as to efficiently transform only waves of the frequency of fork 57 to which it is connected, and which corresponds to the modulation frequency for calling that station, it will be advisable, however, to avoid the fork relays of the uncalled stations being put into operation by successive transient 75 resonance effects resulting from those components of speech modulation as may coincide with the natural time period of the various forks. With that end in view, forks having natural time periods as widely separated as possible from the focus of the speech frequency spectrum shall be chosen and then a suitable filter circuit 26 shall be used to suppress right at their origin, i. e., in the microphone system, such components of the speech 80 as coincide with the modulation frequencies used for effecting calls, having care, however, to restrict the filter losses to the fork frequencies exclusively so as not to distort the speech by excessive curtailment of those 85 components which determine its intelligibility.

Let us now consider a few possible conditions of operation of the system, when the detector 56 is connected say to the coupling arrangement for f^1 , as illustrated.

(a)—One of the distant stations of the network transmits an unmodulated carrier wave of frequency f^1 , which may be the stand-by frequency. Under those conditions, there 100 will appear at terminals 60 from the distant station a corresponding alternating E. M. F., which will be transmitted to the input terminals of 56 through the selective coupler 48^a—50^a—51^a—53 which will give rise, in 105 the output circuit of 56, to a direct current of constant mean value. This constant current will operate the relay 40 through the primary system of 14^a and the back contacts of relays 41, 47 and 43. It is obvious that this direct 110 current flowing the primary system of 14^a will be without effect on its secondary. The closing of busy relay 40 will, on one hand operate the busy signal 38 and, on the other hand, will prevent all possible operation of 115 transmitter starting relay 41 through the receiver being eventually lifted off the hook 42.

(b)—One of the stations transmits a carrier-wave of frequency f^1 also but modulated at a frequency other than that of the fork 57 120 at the station considered. The effect of this transmission on the stand-by apparatus of the receiver in question will obviously be the same as that of the preceding case, since trap circuit 13 practically short-circuits that component of the detected current which corresponds to the unresonant modulation frequency and thereby prevents it from being transferred on to fork relay 57 through transformer 14^a, fork relay 57 being, for that mat- 125 130

ter, also unresonant. While the local operator will not, under those conditions, be able to set his transmitter into operation, it may at times be desirable that he be able to listen in to a conversation offering general interest in the operation of the network. A monitoring relay 47, operated by a push-button 46 on the desk set, has therefore been provided in order to enable him to connect his receiver 11 with the output of detector 56 through transformer 12, by substituting the primary of the latter for the stand-by relay 40, transformer 14^a and trap 13, by means of one of the make contacts of relay 47 without, however, unlocking his transmitter starting equipment.

(c) One of the stations transmits a carrier wave of frequency f^1 modulated at the natural frequency of trap circuit 13 and hence at that of fork 57. Under those conditions, there will be obtained, at the output of detector 56, a unidirectional current the mean amplitude of which will vary at the frequency of trap circuit 13. The latter will then behave as a very high impedance for the low frequency component and will hence give rise to a large potential drop across its terminals. The primary winding of 14^a will therefore be subjected to an alternating E. M. F. corresponding to that of the modulation of the calling carrier wave. This E. M. F. will be transferred across the secondary which will in turn operate the winding 58 setting 57 into vibration.

As stated above, the vibration of fork 57 will cause the operation of the drop relay 20. The drop will in turn operate the ringing relay 43, the operation of which will, on one hand result in the closing of the circuit of bell 45 and call lamp 44, and, on the other hand connect the telephone transformer 12 to the output of detector 56 in place and instead of 14^a and 40. The switching out of the latter will prevent sustained operation of the busy lamp 38 and locking of starting relay 41. The operator at the called station considered may therefore lift the receiver off 42 and thereby close the starting relay 41 which will in turn make a contact at the starting terminals 34 of the transmitter through one of the back contacts of monitoring relay 47 and battery 22, on one hand, and, on the other hand will cause the bell 45 to cease operating by opening its circuit.

It will be understood that by placing battery 22 on the starting terminals 34, the transmitter 31 which may be an electron-discharge tube will be started. If there be any modulating potential at the terminals 33, the high frequency current generated by the transmitter will be modulated thereby.

The communication will thus be established between the called station and the station having transmitted the call. On replacing the receiver at 42 at the end of the communication, call lamp 44 and bell 45 will give the

"through" signal informing the operator that he must lift the drop of relay 20 and thereby restore the stand-by connections.

It will be noted that the exciting windings of shift-over relays 54, 55, are connected in parallel with starting terminals 34 of the transmitter 31 through one of the back contacts of ringing relay 43. They will therefore be operated simultaneously with the starting equipment branched at 34 providing, however, that ringing relay 43 has not been operated just previously to the receiver being lifted off the hook. In case ringing relay 43 would not have operated previously, which would correspond to a call initiated by the local station, the shift-over relays 54, 55, would then be operated simultaneously with the starting equipment connected at 34 and transmission would then take place on frequency f^1 whilst receiving would automatically be carried out on frequency f^2 . It will be understood that transmitter 31 generates both frequencies f^1 and f^2 ,—frequency f^1 being transmitted and f^2 being suppressed, if the arrangement 48—50—51—53 be connected to the transmitter; and frequency f^2 being transmitted and f^1 being suppressed, if the arrangement 48—50—51—52 be connected to the transmitter. There will thus be realized a duplex signalling system in which transmission will automatically take place on f^1 and reception on f^2 if it is the station considered which initiates a call, but in which the opposite will automatically occur if the station sets his apparatus into operation as a result of a received call.

Referring now to Fig. 2, there is shown a diagrammatic representation of another mode of carrying out the invention which comprises the use of a three-electrode tube detector for rectifying the carrier wave in place and instead of the schematic detector 56 of Figure 1 and also of a second three-electrode tube 16 for rectifying the low-frequency alternating component of the calling modulation. Tubes 3 and 16 have their filaments heated by the common source 7 through steady or ballast resistors 5 and 18, voltmeters 4 and 17 being branched across their respective filament terminals in order to measure the voltage applied thereto. The grids of tubes 3 and 16 are connected to the slider of a potentiometer 9 respectively through the carrier-wave input circuit 1—2 and the input circuit 14—15 of the low-frequency calling device. Potentiometer 9 is branched across a battery 6 intended to suitably bias the grids with negative potential. Capacity 10, branched across the potentiometer slider and the positive terminal of battery 6 operates in bypassing oscillations around the potentiometer resistance. The output circuits of both tubes are also fed off a common source 8. The output circuit of tube 3 is connected to the various elements

of the receiving apparatus in a manner similar to that of the detector 56 of Figure 1.

One of the main advantages of the diagram of Figure 2 is that it enables the use of higher modulation frequencies for effecting the selective calls, for it is obvious that the operation of tube 16 which translates the low-frequency component of the carrier wave into a unidirectional current for the operation of the drop relay 20, is not limited to the lower acoustic frequencies as is the case with the fork relay 57 of Figure 1. It will be apparent that the use of higher modulation frequencies for effecting calls will do away with the necessity of suppressing, by means of the filter 26 in the microphone system 24-25, the higher speech components which are useful in maintaining the natural characteristics of the speaker. On the other hand, in those stations provided with but low transmitting power and making use of highly resonant circuits, care will have to be exercised not to modulate the calling carrier wave at an excessive frequency for it can be shown that the same would involve a decrease in transmission efficiency resulting from the virtual untuning of the circuits due to modulation. In fact, a carrier wave of frequency f^1 modulated at a lower frequency F^b gives rise to waves of frequencies $f^1 - F^b$, f^1 and $f^1 + F^b$. It will thus be seen that a portion of the total power of the unmodulated wave f^1 will appear in the form of waves of different frequencies which, in view of the highly resonant circuits used, will not be transmitted as efficiently as the wave f^1 itself.

In this figure there is shown a push-button 37 used for the operation of relay 30 through battery 22. The operation of this relay results in the substitution, during the calling period, of one of the low-frequency sources 28, 29, to the microphone system 24-25-26 normally branched across modulation terminals 33 of the transmitter 31.

In the case of a network wherein communications between various stations are not very frequent, it will be possible to effect an economy by switching the second tube 16 out of circuit during the stand-by period providing, however, that it be automatically re-inserted in the circuit as soon as a call is despatched by any other station of the network. Figure 2 shows a diagrammatical form of realizing this disposition. It will suffice to open the switch 23 normally closing the filament circuit of tube 16 and then to utilize, in parallel with 23, one of the "make" contacts of relay 40 in order to restore the closing of same following the arrival of any carrier-wave.

The output terminals 32 of the transmitter are branched to an output coupler 36-35-E which may lead to an antenna, a loop, or a line circuit in accordance with known methods.

65 The low-frequency sources 28, 29, for mod-

ulating the calling carrier wave may be constituted by ordinary microphone hummers or tuning fork oscillators operating in front of the microphone, providing the filter 26 be simultaneously put out of circuit, or else by utilizing one of the amplifying or modulating tubes as a low frequency oscillator during the calling period. In the latter case, it will be preferable to make use of circuits comprising no magnetic cored inductances in order to avoid that the fundamental frequencies thereby obtained for calling modulation be not accompanied by harmonics which might operate the fork relays of other stations than the one called by a given fundamental.

It goes without saying that the vibrating relay has been represented schematically by a tuning fork relay 57 and that, in accordance with the invention, the same may be replaced by any equivalent vibrating relay, such as vibrating reed relays, etc. This remark also holds good as regards the other switching relays represented only in their schematic form. In particular, the drop relay 20 may be replaced by a polar relay the armature of which will be deviated in one direction by the voltage appearing across the by-passing condenser 19 and thereby establish contact 21, and which will be deviated in the opposite direction by an opposite voltage resulting from the "through" signal and thereby restore the stand-by connections. In a similar manner, the coupling units 48-50-51-53 and 48-50-51-52 of Figure 1 may be replaced by the elementary couplers of Figure 2. Different batteries 22 have been shown in order to simplify the diagram of connections, but it must be understood that these batteries may merge into a single common battery in accordance with well-known common battery practice. Lastly, it will be possible to insert amplifiers before and following either or both tubes 3 and 16 as well as before and following the schematic detector 56.

Having thus described the invention, I claim:

1. In a high frequency communication system, a signalling station comprising a transmitter, a receiver, a detector, a distinctive signalling circuit normally connected to said detector, means including a monitoring key for disconnecting said distinctive circuit from said detector and connecting said receiver thereto without starting said transmitter.

2. In a direct selection polystation communication system, a plurality of signalling stations each having a transmitter and a receiver, means whereby any station may directly selectively call any desired station only and means whereby the transmitters of the undesired stations are locked when said desired station is called.

3. In a high frequency communication system, a plurality of signalling stations each having a transmitter and a receiver, each sta-

75

tion having a common stand-by high frequency and a distinctive stand-by frequency, means whereby the transmitter of any station may send out the stand-by high frequency and the distinctive stand-by frequency of the desired station, the stand-by high frequency locking the transmitters of the undesired stations and the distinctive stand-by frequency causing a signal at the desired station.

4. In a communication system, a transmitter, a receiver, a coupling unit passing only a given first frequency, a second coupling unit passing only a given second frequency, shift-over relays, a signalling device, starting equipment for said transmitter, said relays normally and simultaneously connecting the first coupling unit to said transmitter and the second coupling unit to said receiver, and means whereby said starting equipment may start said transmitter and shift said relays to interchange the connections of said coupling units with said transmitter and receiver if said signalling device has not been operated just previously to said starting equipment and yet only start said transmitter if said signalling device has been operated just previously to said starting equipment.

5. In a communication system, a transmitter, a receiver, a coupling unit passing only a given first frequency, a second coupling unit passing only a given second frequency, and means for simultaneously assigning any one of said coupling units to said transmitter and the other of said coupling units to said receiver, selectively.

6. In a high frequency communication system, a signalling station comprising, distinctive signalling apparatus responsive to a distinctive signal, a busy relay, a receiver, a receiver hook, a detector, a transmitter, a ringing relay responsive to operation of said apparatus to give signal and to de-energize said busy relay, a transmitter starting relay under series control of said hook and said busy relay, said transmitter starting relay being operated by said hook to place said receiver in communication with the detector and to start said transmitter.

7. In a high frequency communication sys-

tem, a signalling station comprising a receiver, a transmitter, distinctive signalling apparatus responsive to a distinctive signal, a busy relay, a transmitter starting relay, a receiver hook, a detector having one output terminal connected thru said apparatus and busy relay to a back contact of said transmitter starting relay, said terminal also being connected thru said receiver to the forward contact of said transmitter starting relay, the armature of said busy relay being in series with said hook and said transmitter starting relay, the other output terminal of said detector being connected to the armature of said transmitter starting relay.

8. In a high frequency communication system, an electron discharge tube detector having a trap circuit tuned to a distinctive frequency and a busy relay in its anode circuit, a rectifier circuit connected across said trap circuit and comprising a second electron discharge tube, the cathode heating circuit of said second tube having in its path an armature of said busy relay, said armature being normally open, said busy relay causing said second tube to function and operating a busy signal when a stand-by frequency is impressed on said detector.

9. In a high frequency communication system, a detector having an output circuit which includes a trap circuit, a rectifier circuit connected across said trap circuit and including an electron discharge tube, and means in said output circuit for controlling the cathode heating current of said tube.

10. A high frequency communicating system comprising at least two stations each having a transmitter and a receiver, said stations having a common stand-by frequency, said transmitters each having means for sending selectively the stand-by frequency and a second different frequency only, said receiver having means for receiving said frequencies only, means whereby any station, if initiating a call, must transmit on the stand-by frequency only and receive on the second frequency only, and, if receiving a call, must receive on the stand-by frequency only and transmit on the second frequency only.

LUCIEN BÉGIN.
